FLOWER DISPLAY BOX

Edgar L. Gould, Rochester, N. Y., assignor to E. E.
Fairchild Corporation, Rochester, N. Y., a cor-
poration of New York

Application April 5, 1938, Serial No. 200,248

5 Claims. (Cl. 206—44)

The present invention relates generally to flower boxes and more particularly to that type of box which may be stored in considerable quantity in flat or collapsed positions for easy, quick 5 erection to permit of the ready insertion of the flowers, the primary object of the invention being the provision of a box of this type and an insert therefor, the latter of which is provided with flower holding means as well as means cooperat- 10 ing with the box in a manner to hold the flowers in one position within the box irrespective of whether the latter is laid flatwise, sidewise or upended.

More specifically, the present invention aims to 15 provide an insert for a flower display box, having means whereby the flowers may be readily disposed in connection with the insert and the latter subsequently readily and easily inserted in 20 the box so as to cooperate with the latter in the subsequent immovable support of the flowers to the end that the box may be shifted from one 25 position to another and stood up endwise to better display its contents without danger of the flowers falling or becoming injured by reason of contact with the box.

In the accompanying drawings which illustrate the present invention and form a part of the specification:

Figure 1 is a plan view of the blank of the im- 30 proved box and insert in detached relation.

Figure 2 is a perspective view of the improved box set up, with the insert adjacent thereto and ready for insertion therein.

Figure 3 is a central longitudinal sectional view 35 through the box closed, with the insert therein.

Figure 4 is a vertical transverse sectional view taken therethrough substantially on the line 4—4 of Figure 3.

Figure 5 is a perspective view of the closed box 40 with the insert therein, showing the same up- ended in a convenient display position.

Figure 6 is a top plan view of an insert show- 45 ing a slightly modified form.

Figure 7 is a longitudinal section through the 45 box showing the insert of Figure 6 in position therein.

Figure 8 is a vertical transverse section taken therethrough substantially on the line 8—8 of Figure 7.

Figure 9 is a top plan view of another insert 50 illustrating a further modification.

Figure 10 is a longitudinal section through the box showing the insert of Figure 9 therein, and

Figure 11 is a vertical transverse section taken 55 on line 11—11 of Figure 10.

Referring now to these figures, the invention contemplates what is commonly known as a window display box formed of a blank as shown in Figure 1, including a bottom 10, sides 11 and 12, and a top 13, which in the blank are continuations of one another, having fold lines 14 therebetween so that they may be folded into the rectangular shape shown in Figure 2. The terminal side 12 at one end of the blank opposite to the bottom 10 is provided along its free edge with 10 a connecting strip 15 bendable along fold line 16 between the same and the side 12, so that, when the sides and top are flexed on the fold lines 14 to the rectangular shape of Figure 2, the terminal strip 15 may be adhesively secured along the free 15 side edge of the bottom 10, preferably upon its upper or inner surface. For this purpose the strip 15 may be provided with an adhesive along one face thereof or an adhesive may be provided along the upper surface of the free edge of the 20 bottom 10 as seen at 17 in Figure 1.

When the sides 11 and 12 and top 13 are folded and the terminal strip 15 adhesively secured to the bottom 10, an elongated rectangular structure is formed which is open at its opposite ends, the 25 latter being adapted to be closed by inner meeting end flaps 18 forming foldable end continuations of the sides 11 and 12, and outer full end flaps 19 forming foldable continuations of the 30 ends of the bottom 10, which close over the inner flaps 18 and have bendable terminal lips 20 which are extended between the top 13 and the adjacent edges of the inner flaps 18 in the final closure.

The sides 11 and 12 as well as the top 13 are 35 provided with elongated sight openings, those of the sides being indicated at 21 and the opening of the top being indicated at 22 and the entire body of the box is covered by a section of transparent material such as Cellophane, as indicated at 23, this section of material extending over the 40 outer faces of the sides and tops and having its terminal side edges extended beneath and adhesively secured to the lower surface of the bottom 10, as indicated at 24 in Figure 4.

As made up in the first instance, the blanks are 45 folded and secured in the rectangular form of Figure 2 in the manner above described and, by reason of the fact that the transparent material or Cellophane section extends loosely over the sides and top, it is obvious that the box body may be 50 laterally collapsed and furnished to florists in this condition whereby prior to their use, and stacked in laterally collapsed conditions, they will occupy a minimum of storage space, ready for quick erection in a single movement from the collapsed 55

position to the position of use shown in Figure 2, so that little time will be required for the proprietor or clerk to adjust the box ready for the insertion of the flowers.

5 The insert provided by the present invention may take several forms, of which the most simple form is shown in Figures 1 to 5, inclusive, consisting as it does of a single rectangular section of cardboard or similar material, as indicated at 25, and of approximately the same size as the bottom 10 of the box, so that when inserted lengthwise within the box, with the closing flaps of the latter in the open position of Figure 2, the flower holding insert 25 occupies the full area of the bottom 10. At its ends the insert 25 is provided with endwise outstanding bendable ears 26 and after positioning of the insert within the box body as just above stated, and closure of the inner end flaps 18, the ears 26 which will, in this position, extend beyond the closed flaps 18, will be bent upwardly when the outer flaps 19 are closed and will thus upstand between the inner and outer flaps 18 and 20, so that the former serve to effectively confine the insert 25 closely against the bottom 10.

10 For the support of the flowers, the flat cardboard insert 25 may have along its median longitudinal portion a series of zigzag kerfs or slits forming a series of alternately oppositely projecting overlapping tongues 21, between which portions of the stems of the flowers may be extended. The insert is also preferably provided at a point intermediate its ends and upon opposite sides of the line of tongues 21, with oppositely arranged 15 kerfs or slits defining curved tongues 28 beneath which the opposite ends of an elastic band 29 may be anchored, the band extending over the stems of the flowers to avoid danger of their lateral displacement from beneath the tongues 21.

15 Obviously, with this form of insert, the ends of which are thus securely held between end closures of the box to prevent the insert from movement bodily away from the box bottom 10, the box in its closed completed form shown in Figures 3, 4 and 5 may be laid on its side or upended as in Figure 5 without danger of the flowers falling against the sides or top of the box and with every assurance that the flowers will be held firmly in upright position against the bottom of the box whereby uniformly effective display will continue, especially with the box in the upended position of Figure 5, until the end closure flaps are released.

20 With the single piece insert 25 of Figure 2, there is, however, the possibility that the weight of the flowers may cause such longitudinal flexure of the insert as to tend to pull its anchoring ears 26 from beneath the inner end flaps 18 and, in order to avoid this possibility, I may provide the insert 30 of Figure 6, the body of which is in all respects the same as the insert 25 of Figure 2, with its stem holding tongues 21a, its endwise extending locking ears 26a and its elastic band holding tongues 28a. The insert 30, however, is additionally provided along its longitudinal side edges with laterally extending narrow strips 31 adapted to be bent upwardly by reason of the fold lines 32 between the same and the body of the insert so as to upstand along the lower inner portions of the side walls 11 and 12 of the box, as plainly seen in Figures 7 and 8, below the windows 21 of said side walls. In this way the upwardly bent side strips 31 of the insert serve to lend lengthwise stability and rigidity to the body 25 of the insert in order to defeat any tendency of

the latter to flex in the direction of its length under the weight of the flowers carried thereby.

25 I may also utilize an insert 33 as shown in Figure 9, having its body provided with endwise projecting locking ears 26b and with flower holding tongues 27b and 28b, the same as those shown in connection with the inserts of Figures 2 and 6. The insert 33 may, however, be provided with full side portions 34 instead of the side strips 31 of Figure 6, that is, side portions 34 which are of 10 approximately the height of the sides 11 and 12 of the box. These side portions will, of course, be joined to the body by fold lines 35 and it will be necessary that they have window openings 36, the latter of which are of slightly greater proportions than the window openings 21 of the box sides 11 and 12. In this way, the insert, having the full side extensions 34, is not only longitudinally reinforced by these side extensions but the latter cooperate with the sides of the box after the 15 insert is placed therein to reinforce the box itself.

20 It is obvious that in providing a box and a box insert of the present type, the invention promotes considerable advantage by reason of the fact that the insert is in its effective position 25 held snugly against the bottom of the box without requiring the operator to do anything to bring about this result. It is plain that upon disposition of the insert within the box, the inner end flaps 18 are then folded inwardly in the same 30 manner it would in any event be necessary. The anchoring ears outstanding endwise from the insert will thus project beyond the end flaps 18 and beneath their lower edges and will be folded upwardly between the inner end flaps 18 and the 35 outer end flaps 19 when the latter are folded upwardly preparatory to the extension of their locking tongues 20 between the upper edges of the inner end flaps 18 and the top 13 of the box.

40 What is claimed is:

1. A flower display box having foldably united bottom, side, and top walls forming an open-ended body, the top and side walls having window openings and the side and bottom walls having end closure flaps of which the flaps of the bottom wall overlie the flaps of the side walls in the closed position, and a flower holding insert consisting of a flat body adapted to closely overlie the bottom of the box and having flower holding means, the said insert being movable into the box 45 endwise of the latter and being provided with endwise projecting members bendable with respect thereto and extending in the closed position of the box angularly with respect to the insert between the inner and outer closing flaps 50 of the body.

2. A flower display box comprising an endwise open body including bottom, side, and top walls, of which the side and top walls are provided with window openings and are foldably in connection with one another and with the bottom, oppositely closing end flaps hingedly in connection with the side walls and having their lower edges overlying the end portions of the bottom in the closed position, end flaps having 60 locking end lips and overlying the side wall flaps in the closed position, and a flower holding insert for the box consisting of a flat body overlying the box bottom and having flower holding means, said insert having endwise projecting 65 locking ears extending beneath the side wall flaps and positioned angularly with respect to the insert between the said side wall flaps and the closure flaps of the box bottom.

3. A flower display box having foldably united 70

bottom, side and top walls forming a laterally collapsible open-ended body, certain of said walls having window openings through which the contents of the box in erected position may be viewed, certain of said walls having endwise extending hinged closure flaps overlapping one another in the closed position, and a flower holding insert having a flat body overlying the bottom wall of the box, said insert being endwise shiftable into the box body and having endwise projecting portions bendable with respect thereto at the ends thereof, and extending angularly with respect to said insert in the closed position of the box, between the overlapping closure flaps

at the closed ends of the box and beneath the lower edges of certain of said flaps to thus confine the insert against the bottom wall.

4. A box as claimed in claim 3 in which the body of the insert is also provided with upwardly 5 projecting longitudinal side extensions at the inner surfaces of the box side walls.

5. A box as claimed in claim 3, said insert having longitudinal side portions projecting angularly upwardly with respect to its body portion and along the box side walls for the full 10 height of the latter.
